(57) **CLAIM**

We claim the ornamental design for a latch, as shown and described.

DESCRIPTION

FIG. 1 is a perspective view of an embodiment of a latch according to the present invention.

FIG. 2 is a front elevational view of the latch of FIG. 1.

FIG. 3 is a first end elevational view of the latch of FIG. 1.

FIG. 4 is a second end view, opposite the first end, of the latch of FIG. 1.

FIG. 5 is a top plan view of the latch of FIG. 1.

FIG. 6 is a bottom plan view of the latch of FIG. 1.

FIG. 7 is a perspective view of another embodiment of a latch according to the present invention.

FIG. 8 is a front elevational view of the latch of FIG. 7.

FIG. 9 is a first end elevational view of the latch of FIG. 7.

FIG. 10 is a second end view, opposite the first end, of the latch of FIG. 7.

FIG. 11 is a top plan view of the latch of FIG. 7; and,

FIG. 12 is a bottom plan view of the latch of FIG. 7.

The broken lines environment is for illustrative purpose only and forms no part of the claimed design.
